CLAIM

We claim the ornamental design for the telescoping plunger, as shown and described.

DESCRIPTION

FIG. 1 is a front perspective view of the telescoping plunger where the plunger is in an extended position.

FIG. 2 is a front view of FIG. 1.

FIG. 3 is a right side view of FIG. 2.

FIG. 4 is a back side view of FIG. 2.

FIG. 5 is a left side view of FIG. 2.

FIG. 6 is a top view thereof; and,

FIG. 7 is a bottom view thereof.

The broken lines in the figures depict environmental subject matter only and form no part of the claimed design.
